US00D830196S

(12) **United States Design Patent** (10) **Patent No.:** **US D830,196 S**
Porchia et al. (45) **Date of Patent:** **** Oct. 9, 2018**

(54) **STORAGE BAG**

(71) Applicant: **S.C. Johnson & Son, Inc.**, Racine, WI (US)

(72) Inventors: **Jose Porchia**, Greenfield, WI (US); **Brian C. Dais**, Saginaw, MI (US); **Keegan E. Burggren**, Midland, MI (US); **Imtiaz A. Musaliar**, Racine, WI (US); **Erica Eden Cohen**, New York, NY (US); **Charles P. Althoff**, Brooklyn, NY (US)

(73) Assignee: **S. C. Johnson & Son, Inc.**, Racine, WI (US)

(**) Term: **15 Years**

(21) Appl. No.: **29/624,615**

(22) Filed: **Nov. 2, 2017**

Mar. 15, 2013, now Pat. No. Des. 723,384, and a continuation of application No. 29/449,727, filed on Mar. 15, 2013, now Pat. No. Des. 723,937.

CLAIM

The ornamental design for a storage bag, as shown and described.

DESCRIPTION

FIG. 1 is a front view of a storage bag showing our new design;

FIG. 2 is a left side view thereof;

FIG. 3 is a right side view thereof;

FIG. 4 is a top view thereof; and,

FIG. 5 is a bottom view thereof.

The broken lines in the figures show portions of the storage bag that form no part of the claimed design.

The dot-dash lines in the figures show boundaries that form no part of the claimed design.
